CHARLES H. HUGHES, OF SYRACUSE, NEW YORK, ASSIGNOR TO SEMET-SOLVAY COMPANY, OF SOLVAY, NEW YORK, A CORPORATION OF PENNSYLVANIA.

TUBULAR RECUPERATOR FOR RETORT COKE-OVENs.

1,120,146.

Specification of Letters Patent.

Patented Dec. 8, 1914.

Application filed June 19, 1912. Serial No. 704,555.

To all whom it may concern:

Be it known that I, CHARLES H. HUGHES, a citizen of the United States, residing at Syracuse, in the county of Onondaga and State of New York, have invented certain new and useful Improvements in Tubular Recuperators for Retort Coke-Ovens, of which the following is a specification.

This invention relates to improvements in recuperators, designed for use in connection with retort coke ovens, and the invention relates especially to the construction of the heat interchangers for utilizing the heat of the waste or burnt gases for heating the air and other elements forming the combustible mixture.

The invention relates particularly to an improvement in the devices shown and described in my former application, Serial No. 536,807, bearing date January 7, 1910.

The object of the invention is to provide novel, simple and effective recuperators or heat interchangers for retort coke ovens, each comprising a number of individual detachable tubular flues, which are disposed directly in the path of, and are heated by the waste or burned gases, as they pass from the ovens to the chimneys.

A further object is to provide a tubular heat interchanger which is capable of supplying measured volumes of pre-heated air and gas to one or more ovens simultaneously, and wherein the air and gas flow uninterruptedly to the combustion chambers, while the products of combustion flow uninterruptedly in one direction through each of the combustion chambers and the heat interchangers, into the chimney, thereby obviating the necessity of providing any operating dampers or other reversing mechanisms periodically, as in many of the former systems.

A further object is to provide novel and simple means for applying each of the tubular flues, for facilitating the instalment, as well as the inspection and repairing of said parts, the said means capable of preventing damage or impairment due to the expansion and contraction of said flues or their supports.

A further object is to improve the construction and to reduce the number of parts as compared with the devices shown in my former application. And a particular object of my invention is to provide a more

direct passage for the air and gas through the interchangers to the combustion chambers, also a more direct passage for the products of combustion from the ovens to the chimney, and in addition, to conserve 60 the fuel, and at the same time to produce a higher degree of combustion and temperature from a given quantity of fuel.

Other features and parts of the invention will be understood from the detailed description which follows, and by reference to the accompanying drawings, which form a part of this specification and in which—

Figure 1 is a vertical longitudinal section substantially on line 1—1 of Fig. 2; showing generally the construction of one of the ovens and its individual recuperator. Fig. 2 is a broken vertical cross-section substantially on line 2—2 of Figs. 1 and 8; showing the disposition and arrangement of a number of ovens and recuperators united in a single structure. Fig. 3 is an enlarged detail section; showing the construction and arrangement of one of the air or gas flues; also showing the resilient means for holding the flue in place. Fig. 4 is a broken horizontal section taken on line 4—4 of Fig. 1. Fig. 5 is an enlarged detail section; showing a modification of the means for controlling the inlet of the air to the flues. 85 Fig. 6 is a bottom plan view of the same. Fig. 7 is a broken vertical longitudinal section on line 7—7 of Fig. 2; showing the arrangement of the ports which deliver the heated air and gas to the combustion chambers; also showing auxiliary piping for delivering cold gas to the combustion chambers. Fig. 8 is a vertical longitudinal section on line 8—8 of Fig. 2; showing the adaptation of the heat interchanger for 90 heating the gas; also showing the means for distributing the heated gas to the combustion chambers of one or more ovens. Fig. 9 is a vertical cross section through the gas recuperator, the gas risers and the oven linings, taken on line 9—9 of Fig. 1. Fig. 10 is a plan section through one of the gas and air boxes, taken on line 10—10 of Fig. 11; showing the slides for controlling the 95 flow of gas and air to the oven linings. Fig. 11 is a vertical section of the same, taken on line 11—11 of Fig. 10.

In the drawings, 2 represents a series of longitudinal chambers which are disposed parallel to each other, and these are sepa- 110

rated by means of vertical partitions or walls 3.

4 represents the coke ovens or chambers which are disposed within the chambers 2, 5 and these are each inclosed on their four sides by the usual oven linings 5, 3 and 7. The opposite side-linings 5 are preferably hollow, and subdivided into a number of similar combustion conduits or passages 8, 10 arranged one above the other, which extend the full length of the oven cavities 4, and these conduits communicate successively at their opposite ends, by means of ports 9, for the passage of the products of combustion 15 and gas and air, as indicated by the arrows in Fig. 1. Under this arrangement the combustible mixture or fluid which is supplied to the right hand end of the uppermost conduit 8, will pass to the left, and 20 thence downwardly through one of the ports 9 into the next conduit, thence to the right, and so on, back and forth in a continuous flow, until it reaches a sub-chamber 10, which is arranged directly beneath, 25 and by means of which, the bottom 7 of each of the ovens is heated. After the burnt gases enter the chamber 10, they pass horizontally to the opposite end and then downwardly through a vertical passage 11 30 and enter another horizontal chamber 12, which is arranged between the walls 3 and horizontal partitions 13 and 14. From the chambers 12, the gases are discharged into a common chimney 15, which receives the 35 waste products of all the ovens, and which may follow any of the usual constructions. 16 represents a second vertical discharge passage which connects the opposite ends of the chambers 10 and 12. The passages 40 11 and 16 are controlled by sliding gates or dampers 17 and 18 which are preferably operated for alternately opening and closing the passages 11 and 16, as indicated by the full and dotted lines in Fig. 1.

45 In ovens of this type, the coal is supplied to the coking chambers 4 by gravity through charging ports 4', where it is burned or coked by means of a combustible gas, which is usually supplied to the linings 50 of the ovens by pipes, as 19, which pass through walls 20, which close the opposite ends of the oven linings 5. The gas employed for coking the coal is mixed with air for the purpose of supplying the 55 requisite amount of oxygen for completing the combustion, and in ordinary practice the air is pre-heated before it reaches the conduits 8 and mingles with the gas. In the present invention, both the gas and air 60 are heated before they are delivered to the combustion chambers, by a series of novel and simple heat-interchangers or recuperators, which will now be described.

For convenience in explaining my improvement, I have illustrated a battery of

three separate ovens, as best seen in Fig. 2. The ovens are provided with independent recuperators A and B, each of which comprises a plurality of tubular flues 21, each flue preferably consisting of one piece, which may be made out of fire-clay or any other refractory substances, or may consist of metal, or a suitable composition. The flues 21 are preferably arranged vertically in the chambers or passages 12 directly in the path of the hot waste gases, which impinge against and envelop and heat the said flues. The preferred arrangement of the tubes 21 is illustrated in Fig. 4, where they are shown disposed in a number of staggered rows. Referring to Fig. 3, the tubes 21 pass upwardly through perforations 22 formed in the lower partitions 14, while their upper ends enter sockets 23 which are formed in the lower ends of a series of 85 thimbles 24, which are carried by the upper partitions 13. The bore of the thimbles 24 is preferably the same as that of the tubes 21. The thimbles 24 are preferably molded or cast out of fire-clay or other suitable substances, which will stand a high temperature, and these parts are then set in the masonry comprising the partitions 13. Each thimble is provided with a circumferential flange or rib 24', which serves 90 to prevent the displacing of said parts, and at the same time the said flange tends to prevent the leakage of the air or gas around the thimbles. Furthermore, by the use of the thimbles, in case the upper partition 13 95 burns out or otherwise becomes impaired, at the intersection of the flues 21, the trouble may be quickly remedied by removing and replacing the thimbles.

25 represents a packing, preferably asbestos, which is disposed between the upper ends of the tubes and the thimbles.

The perforations 22 in the partitions 14 are preferably in the form of inverted funnels, the smallest diameter of which is 110 slightly greater than the diameter of the tubes 21, so as to allow for the lateral expansion of the said tubes when heated up.

26 represents asbestos or similar packing rings which surround the pipes 21 and fill 115 the perforations 22. The packings 25 and 26 prevent the escape of the unburnt as well as the waste gases through the partitions 13 and 14, and at the same time serve to cushion the tubes 21, thus preventing the harder 120 substances comprising the tubes and partitions from contacting with each other. The tubes 21 being disposed in the chambers 12 directly in the course of the waste or burnt gases as they pass from the ovens to 125 the chimney, may be heated to any desired extent, thereby providing a convenient, effective and economical means for pre-heating the air and the gas, both of which are preferably admitted to the lower ends of 130

the tubes 21, by means of horizontal tunnels or passages 27 and 27', which are arranged beneath and parallel to the chambers 12, and which communicate with the atmosphere by means of inlet openings 28 at one end of the tunnels. The inlets 28 of the tunnels 27 are normally open for the admission of the air to the flues 21, and the volume of air allowed to pass through each 10 of the said flues is controlled by regulating devices which will later be described.

The intermediate recuperator B, is intended only for heating the gas, and the latter fluid is supplied to the lower ends of the 15 tubes 21 by means of a common main 29, which is disposed at one side of the tunnel, to which is connected a series of lateral branches 30, which deliver the gas to the individual flues 21 by means of angular pipes 31 and nozzles 32. The nozzles 32 preferably extend part way into the tubes 21 (see dotted lines Fig. 5), and are detachably connected to the pipes 31 by means of unions 33. By this arrangement the nozzles may be 5 disconnected and the pipes 31 swung to one side or the other, so as to permit the removal, insertion or repairing of the tubular flues.

34 represents valves disposed in the pipes 30 31 for controlling the flow of the gas into the heating flues.

The gas for one or more of the recuperators B is supplied by a common main 35, which connects with the main 29 by a vertical pipe 36. The opening 28 at the end of the tunnel 27' beneath the gas recuperator is preferably tightly closed by a door 37 through which the main 29 passes. The object of this door is to prevent any air 40 entering the tunnel and mixing with and igniting the gas while it is being heated.

In my former application referred to, the air tubes, corresponding to the flues 21 of the present device, are disposed vertically 45 and pass through an upper, an intermediate, and a lower partition in which said tubes are closely fitted in vertically aligned apertures in the three partitions. Owing to the high temperature of the two waste gas 50 chambers lying between these three partitions, there is a greater expansion and contraction of the intermediate partition than of the upper and lower partitions. This produces a dangerous strain upon the middle portion of the air flues, causing the said flues to bend or warp to such extent that it is difficult to either insert or remove the said parts. Furthermore, the said strain frequently cracks or breaks the air flues and 55 thus interferes with the perfect and continuous operation of the furnace. To obviate the aforesaid troubles, and to prolong the usefulness of the air flues 21 in the present device, I have eliminated the intermediate partition, and provide but one di-

rect chamber or passage, as 12, for the waste gases to pass from the ovens to the chimneys. Under this arrangement, in connection with resilient securing means which are applied to the lower ends of the air flues 21, 70 a higher efficiency is attained and at the same time less labor and expense of maintenance are entailed. The elimination of one partition and one of the chambers in each heat-interchanger, as described, results in 75 a less tortuous course for the products of combustion, which tends to strengthen the draft, thereby producing a higher temperature in the oven linings, as well as, in the waste chambers 10 and 12, and the flues 21. 80 This effects a more rapid coking of the coal. Furthermore by thus increasing the temperature, a more perfect combustion of the fuel is effected, resulting generally in a more expeditious and a more economical operation 85 of the coking system. On the other hand, by the elimination of the middle partitions of my former recuperators, I am able to employ the tubular flues 21 for heating the gas, without danger of the said flues 90 cracking or breaking, which would allow the gas to become ignited and wasted before it reaches the combustion conduits.

During the coking operations the air and gas pass respectively through the tubes 21 95 and the thimbles 24, of the interchangers A and B, into longitudinal chambers 39 and 39', which are arranged between the partitions 13 and the bottoms 40 of the chambers 10. The opposite ends of the chambers 39 and 39' are closed by walls 41. From the chambers 39 the heated air passes through ducts or risers 42 and 43, to the opposite ends of the ovens 4. The heated gas passes from the chambers 39' through similar ducts 100 or risers 44 and 45 to the opposite ends of the ovens 4. The risers 42, 43, 44 and 45 are all disposed in the walls 3 which separate the adjacent ovens. As the air and gas rise in their respective ducts, they flow continuously 105 and discharge into the corresponding conduits of the adjacent linings 5 of the ovens, through ports 46 and 47, and under the arrangement shown in Figs. 1 and 8 the said ports are so disposed that the mixing 110 of the pre-heated air and gas takes place immediately upon the discharging of the said elements into the conduits 8. In order to promote a continuous and perfect combustion, as well as an even heating of 115 the coking chambers throughout their length and height, the separately heated gas and air are delivered successively to the several conduits 8 through the ports 46 and 47, as best seen in Figs. 1 and 8. Under this arrangement the combustible mixture is simultaneously 120 and continuously relayed for boosting the charge at the entrance of each of the conduits 8. By this provision all parts of the ovens can be heated to the same 130

extent, and a direct and even draft maintained throughout the combustion chambers.

Owing to the fact that more or less expansion and contraction takes place in the flues 21, the same as in other parts of the oven structure during the operating periods, I provide adjustable resilient means for holding each of the flues 21 in place. These means comprise floating plates 50 which have counter-sunk perforations 51 in which the correspondingly shaped lower ends of the tubes or flues are fitted, as in sockets, the clear diameter of the said perforations being preferably the same as the bore of the flues. Then at the opposite sides of each flue are disposed screws or bolts 52, which preferably pass through plates 53 and are made fast in a common plate 54 which is rigidly mounted on the under side of each partition 14. The bolts 52 are preferably threaded their whole length and pass loosely through suitable perforations in the plates 50 and 53. The plates 53 are employed for holding the packing rings 26 in place, and these plates are held in place by coil springs 55 which are disposed between the plates 50 and 53. The springs 55 are of sufficient strength to hold the packings 26 in place for preventing leakage of the gases through the partition. 56 represents a stiffer coil spring, which is fitted on the lower free end of each of the bolts 52, one end of said spring bearing against the underside of the plate 50, while the other end of said spring engages a washer 57 which is held in place by a nut 58. Under this arrangement and construction each of the flues 21 is supported and held in place by tension plate 50, a pair of springs 56, a pair of washers 57 and a pair of nuts 58, and any desired tension may be given to the latter springs by the manipulation of the said nuts. By the provision of the springs 56, the linear expansion and contraction of the flues 21 is taken care of, and there is little danger of the flues either warping or breaking on account of the heating and cooling off of said parts. The vertical arrangement of the tubes 21, coupled with the resilient securing means also lessens the tendency of the flues to become distorted, because the entire weight of the flues is supported by the tension plates 50; and these plates will yield whenever any linear strain is exerted. To withdraw one of the flues 21 for repairs or otherwise the attendant should remove the nuts, washers, springs and the floating plate 50, after which the tube may be withdrawn downwardly from the chamber 12 into the tunnels 27 and 27'. To repair a single flue, it is not necessary to shut down the ovens, as the attendant may enter the air or gas tunnels at any time and remove a flue without interrupting the coking operation. In case it is desired to generally repair or overhaul one of the recuper-

ators, the sliding gate 18 should be opened, and the gate 17 should be closed, after which a third gate 59 should be moved upwardly through the partition 14 for closing the chamber 12. When the three gates or dampers have been operated, as last described, the waste gases will pass directly from the chamber 10 through the passage 16, and thence into the chimney 15, without coming into contact with any of the flues 21. 75

For the purpose of regulating the amount of air to be preheated, each of the flues 21 is preferably equipped with a pivoted gate or valve 60, which is carried by the plate 50, as shown in Figs. 5 and 6. By the use of the gates or checks 60 the inflow of the air may be regulated to suit the requirements of the combustion. Any other suitable regulating device may be used instead of the gate 60, and I have illustrated a modification of the said device which comprises a tubular bushing 61, as shown in Fig. 3. Under this latter form of the reducer, a number of the plugs 61 may be provided for each flue wherein the openings through the plugs may be graduated for varying the volume of the air admitted to the flues. 62 represents a clip or a catch carried by each plate 50 for holding the bushing 61 in place.

In the gas recuperator B, the gates 60 carried by the tension plates 50 are perforated at 60' for allowing the insertion of the nozzles 32 which conduct the gas to the flues 21. In this case no adjustment of the gates 60 is required, for the reason that the supply of gas is regulated by the valves 34. 95

64 represents ports through the walls 20, which communicate with the air and gas risers, and which are closed by movable plugs 65, and 66 represents the slides which are disposed in said ports, and these are adapted to be moved back and forth horizontally for controlling the flow of both air and gas from the ducts or risers to the combustion conduits 8. The object of the ports 64 is to permit the flue-operator to examine and regulate the flame in the combustion chambers during the coking operations. The slides 66 are usually disposed at the receiving ends of the combustion conduits, 115 as best seen in Fig. 8.

The gas pipes 19 at one end of the furnace also connect with the main 35. Under this arrangement, if it becomes necessary to shut down the recuperator B for extensive repairs, the gas may be shut off from the main 29 by means of the valve 38, and the gas may be turned on to the pipes 19. Then by opening the damper 18 and closing the dampers 17 and 59, the ovens may all be operated without pre-heating the gas and without loss of time, until the repairs to the recuperator B are completed. 35' represents a second gas main located at the opposite end of the furnace to which the corre- 130

sponding pipes 19 are connected for supplying unheated gas to the opposite ends of the chambers 8, while the recuperator B is shut down.

5. In practice, there are usually thirty or forty coke ovens which are closely arranged in block, as indicated in Figs. 2 and 9, and when applying my improvement to coking furnaces of this class, the recuperators A and B are preferably arranged alternately, as shown. Under this arrangement the recuperators B supply the pre-heated gas to the adjacent linings 5 of three of the coking ovens.
15. It is obvious that the gas supply pipes 29, 30, 31 and 32 may be removed from the tunnel 27', and that the recuperator B may be utilized for pre-heating air the same as the recuperators A, and in such case the gas 20 may be supplied to the combustion chambers 8 by means of the auxiliary pipes 19.

By the use of my recuperators A and B, associated with the feature of the direct and uninterrupted firing, there is less deterioration 25 of the furnace generally, due to the fact that during the entire coking operation, there is practically no change or variation in the heat of combustion, and therefore the range of expansion and contraction and 30 the wear and tear of the parts of the furnace are reduced to a minimum. Furthermore, by the novelty and simplicity of the construction and arrangement of the heat interchangers, and the shortening of the 35 course of the waste gases from the ovens to the chimney, I am able to utilize the strong suction which is usually employed for creating the draft throughout the entire system, in a more direct way, thereby 40 producing a higher degree of temperature in the combustion conduits, as well as in the waste passages. This results in a more rapid and economical coking of the coal, which is very desirable. At the same time owing to 45 the feature of the direct and uninterrupted flow of the pre-heated air and gas to the combustion chambers, and the steady and uninterrupted flow of the products of combustion through all of the chambers to the 50 chimney, a normally high temperature may be maintained with little or no variation throughout the entire coking operations.

The recuperating means herein shown and described are extremely simple and are 55 highly efficient. Coking ovens equipped with my improvement, may be constructed and maintained at less cost, are rendered more durable and quicker acting, and require less attention, renewal and repair, 60 than any other type of furnaces known to me.

Having thus described my invention, what I claim as new and desire to secure by Letters Patent, is—

65. 1. A heat-interchanger, comprising spaced

horizontal partitions, each provided with a series of vertically alining apertures, a tubular thimble disposed in each of the apertures in the upper partition, the lower ends of said thimbles provided with sockets, one-piece flues piercing the apertures in the lower partition and extending vertically across the space between said partitions, the upper ends of said flues nesting in the sockets of said thimbles, and perforated tension-plates disposed beneath and spaced from the lower partition, adapted to receive the lower ends, and to hold the said flues, in engagement with said thimbles.

2. A heat-interchanger, comprising upper and lower partitions spaced apart from each other, and each provided with a series of vertically alining apertures, thimbles disposed in the apertures of the upper partition, the lower ends of said thimbles provided with sockets, one-piece flues disposed in the apertures of the lower partition and extending across the space between said partitions, the upper ends of said flues nesting in the sockets of said thimbles, a perforated tension-plate adapted to support the weight of each of said flues, and a series of springs 90 coöoperating with said plates for resiliently holding said flues in place.

3. In a recuperator for retort coke ovens, the combination with upper and lower spaced partitions each having vertically alining apertures, and a series of thimbles disposed in the apertures of the upper partitions, of a series of tubes piercing the lower partition 100 adapted for carrying a fluid through the space between said partitions for pre-heating said fluid, the upper ends of said tubes interfitting with said thimbles, spring controlled means applied to the lower ends 105 of said tubes adapted for maintaining the connection between said tubes and said thimbles, and means for supplying measured volumes of the fluid to the lower end of each 110 of said tubes.

4. In a recuperator for retort coke ovens, the combination with upper and lower spaced partitions each having vertically alining apertures, and a series of thimbles disposed in the apertures of the upper partitions, of a series of tubes extending vertically through the lower partition adapted 115 for carrying a fluid through the space between said partitions for pre-heating said fluid, the upper ends of said tubes interfitting with said thimbles, spring controlled means applied to the lower ends of said tubes adapted for maintaining the connection between said tubes and said thimbles, and means for increasing and decreasing 125 the linear tension on said tubes.

5. In a recuperator for retort coke ovens, the combination with upper and lower spaced partitions, and a series of thimbles piercing the upper partition, of a series of 130

- 6 tubes piercing the lower partition at points alining with said thimbles, adapted for carrying a fluid through the space between said partitions for pre-heating said fluid, 5 the upper ends of said tubes inserted in sockets formed in the lower ends of said thimbles, for rendering said tubes removable without disturbing other parts of the recuperators, spring controlled means exerting pressure for maintaining the connection between said tubes and said thimbles, and means for removing, replacing and repairing the said tubes without requiring the shutting down of the furnace. 10
- 15 6. In a recuperator for retort coke ovens, upper and lower partitions spaced apart from each other, each of said partitions having vertically alined apertures arranged in staggered rows, bushings in the apertures of 20 the upper partition, tubes capable of being inserted upwardly through the apertures in the lower partition and entering the lower ends of said bushings, adapted to be heated by waste gases passing between said partitions, means for directing measured jets of 25 fluid into the lower ends of said tubes for pre-heating said fluid while passing upwardly from one partition to the other, and resilient means for supporting and holding 30 said tubes in place.
- 35 7. A heat-interchanger, comprising upper and lower partitions spaced apart from each other, and each provided with a series of vertically alining apertures, the apertures in the lower partition being funnel shaped, thimbles disposed in the apertures in the upper partition, the lower ends of said thimbles provided with sockets, one-piece flues vertically arranged in the apertures in 40 the lower partition and extending across the space between said partitions, the upper ends of said flues nesting in the sockets of said thimbles, packing washers for sealing the joint between said flues and said thimbles, packing rings for sealing the perforations in said lower partition, and a perforated tension-plate disposed beneath and spaced from the lower partition, adapted to receive the lower end, and to support the 45 weight, of each of said flues.
- 50 8. In a recuperator for retort coke ovens, the combination of upper and lower partitions spaced apart from each other, and each having vertically alining apertures, thimbles disposed in the apertures of the upper partition, the said thimbles provided with sockets arranged concentric to the apertures in the lower partition, one-piece tubular flues adapted to be inserted upwardly through the 55 lower partition, the upper ends of said flues received by the sockets of said thimbles, the said flues arranged in staggered rows, and each spanning the space between said partitions, a permanent plate mounted on the 60 underside of the lower partition, a pair of bolts carried by said plate and depending at the opposite sides of each of said flues, a floating-plate loosely mounted on each pair of said bolts, said floating-plates having counter-sunk perforations for receiving the lower ends of said flues, and a pair of springs adapted to exert their tension against each of the said floating-plates for yieldingly holding said flues in place. 70
- 65 9. In a recuperator for retort coke ovens, the combination of upper and lower partitions spaced apart and each having vertically alined apertures therethrough, means for heating the space between said partitions, one-piece detachable tubular flues arranged vertically in the apertures of the lower partition, a portion of said flues projecting below the lower partition, thimble bushings in the apertures of the upper partition and having sockets in their lower ends to receive the upper ends of said flues, means for forcing cold fluid upwardly through said flues for pre-heating said fluid while it passes from the lower partition to the upper partition, a series of springs mounted on the underside of the lower partition adapted to exert their tension for holding said flues in place, and a valve for regulating the volume of the fluid which passes upwardly through each of said flues. 80
- 85 10. In a recuperator for retort coke ovens, the combination with the upright walls and top and bottom partitions forming the horizontal waste gas passage, the said partitions having a number of vertically alining perforations, of thimbles disposed concentrically in the perforations in the top partition, one-piece tubular flues disposed vertically in the perforations in the bottom partition, said flues projecting across the space between said partitions, their lower ends extending below the bottom partition, and the upper ends of said flues inserted in the lower ends of said thimbles, tension-plates for receiving the lower ends of said flues, bolts depending from the bottom partition and piercing said tension-plates, nuts carried by said bolts, and a cushion spring carried by each of said bolts, said springs disposed between said nuts and said tension-plates, adapted to exert their tension 90 for holding said flues in place and for permitting said plates to yield during the expansion and contraction of said flues. 95
- 100 11. In a continuous heat-interchanger for retort coke ovens, the combination with a lower, an intermediate and an upper passage, said passages arranged horizontally and parallel to each other, of an upper and a lower partition separating said intermediate passage from the upper and lower passages, each of said partitions having vertically alined apertures arranged in staggered rows, bushings disposed in the apertures of the upper partition, one-piece tubes dis- 105
- 110 115
- 120 125
- 130

posed in the apertures of the lower partition and extending vertically across the intermediate chamber, the upper ends of said tubes entering the lower ends of said bushings, the lower ends of said tubes projecting into the lower passage, means for supplying measured volumes of cold fluid to the lower ends of said tubes, and means for heating the fluid as it passes through the portion of said tubes which spans the intermediate chamber.

12. A continuous recuperator for retort coke ovens, comprising a plurality of tubular flues, a horizontal partition having perforations to receive said flues, thimbles to receive the upper ends of said flues, said thimbles spaced vertically from said partition and coinciding with the perforations in said partition, plates having sockets to receive the lower ends of said flues, bolts depending from said partition and piercing said plates, springs carried by said bolts adapted to exerting their power for holding said flues in engagement with said thimbles, the said springs capable of yielding during the linear expansion of said flues, for preventing warping and breaking of said flues, means for heating said flues, and means for continuously supplying a fluid to the lower ends of said flues to be pre-heated while passing upwardly through said flues and said thimbles.

13. In means for supplying pre-heated air and gas to retort coke ovens, the combination with an upper, an intermediate and a lower chamber, of a partition separating the upper and intermediate chambers, said partition having a series of perforations, a thimble disposed in each of said perforations, the lower ends of said thimbles having sockets, a second partition for separations alining with the openings in said thimble the intermediate and lower chambers, said partition having a series of perforations, one-piece tubular flues piercing the second partition, their upper ends disposed in the sockets of said thimbles, the lower ends of said flues projecting into the lower chamber, means for admitting measured volumes of fluid from the lower chamber into the lower ends of said flues, means for pre-heating said fluid while it flows through the said flues to the upper chamber, and means for increasing and decreasing the volume of the fluid which passes through each of said flues.

14. A pre-heater for gas and air, comprising a number of tubular flues disposed vertically in staggered rows, a horizontal wall provided with perforations for receiving said flues, a second wall arranged above and parallel to the first wall, tubular thim-

bles carried by said second wall and alining with the said flues, the lower end of each thimble provided with a socket for receiving the upper end of the corresponding flue, an apertured plate disposed across the lower end of each of said flues, adapted for supporting the entire weight of the flue, bolts carried by said first wall, and springs carried by said bolts adapted to exert their tension against said plates for holding said flues in engagement with said thimbles, said springs and said plates capable of yielding toward and away from said first wall during the linear expansion and contraction of said flues.

15. A continuous recuperator for retort coke ovens, comprising a series of removable flues, a horizontal partition having perforations to receive said flues, thimbles to receive the upper ends of said flues, said thimbles spaced vertically from said partition and alining with the perforations in said partition, perforated plates arranged below said partition having sockets to receive the lower ends of said flues, bolts depending from said partition and piercing said plates, and springs carried by said bolts adapted for exerting their power for holding said flues in engagement with said thimbles, the said springs adapted to yield during the linear expansion of said flues, for preventing warping and breaking of said flues.

16. The combination with upper and lower spaced partitions, each having vertically alined apertures, of a series of tubes extending through the lower partition, adapted to carry a fluid through the space between said partitions for preheating said fluid, means for interfitting the upper ends of said tubes with the upper partition, and spring-controlled means carried by the lower partition for holding said tubes in place.

17. A heat interchanger, comprising spaced partitions, each having apertures alining vertically, detachable flues piercing the apertures of the lowermost partition and extending vertically and connecting with the uppermost partition, plates disposed beneath the lowermost partition for supporting said flues, and springs adapted for pressing said plates against the lower ends of said flues and for resiliently holding said flues against the uppermost partition.

In testimony whereof I affix my signature in presence of two witnesses.

CHARLES H. HUGHES.
